UNITED STATES PATENT OFFICE

106,592

DESIGN FOR AN ARTIFICIAL FISH LURE

William Franklin Eger, Bartow, Fla.

Application July 8, 1936, Serial No. 63,716

Term of patent 14 years

To all whom it may concern:

Be it known that I, William Franklin Eger, a citizen of the United States, residing at Bartow, in the county of Polk and State of Florida, have invented a new, original, and ornamental Design for an Artificial Fish Lure, of which the following is a specification, reference being had to the accompanying drawing, forming a part thereof.

This is a continuation-in-part of application Ser. No. D-61,002, filed February 7, 1936.

Figure 1 is a side elevation of an artificial fish lure, showing my new design.

Figure 2 is a top plan view.

Figure 3 is a bottom plan view.

The characteristic feature of the invention resides in the elliptical arrangement of dots around the eyes in combination with the bands of color applied to the body of the bait in the configuration shown.

I claim:—

The ornamental design for an artificial fish lure, as shown and described.

WILLIAM FRANKLIN EGER.
